UNITED STATES PATENT OFFICE

CHARLES L. MCCUEN, OF LANSING, MICHIGAN, ASSIGNOR TO GENERAL MOTORS CORPORATION, OF DETROIT, MICHIGAN, A CORPORATION OF DELAWARE

AIR CLEANER

Application filed July 18, 1928. Serial No. 293,644.

This invention relates to a ventilating system for automobile crankcases and particularly to a system of the type in which a portion of the carburetor air supply is taken from the crankcase. It is desirable that the 5 air supplied to the carburetor from the atmosphere be relieved of its dust content by passage through an air cleaner. It is not necessary to clean the vapors drawn from the 10 crankcase for they are relatively free from dust, since the only communication between the crankcase and the atmosphere is through a breather opening which is normally protected by a suitable cowl, screen or a separate 15 air cleaner.

To secure effective ventilation it is desirable that substantially the full intake suction be applied to the crankcase. I have devised a convenient and simple arrangement 20 whereby the carburetor is insured a supply of clean air without materially reducing the suction applied to the crankcase. The arrangement consists in providing a connection between the engine crankcase and the air cleaner 25 at a point where dust separation has been substantially completed. In the case of a centrifugal cleaner, connection is made with the enter of the vortex preferably in line with the outlet conducting clean air from the vortex to the engine intake. By thus locating 30 the crankcase connection I am assured of a maximum degree of suction for the vacuum at this point in the cleaner is very high.

As the crankcase vapors contain a considerable 35 amount of oil I have preferred to make the connection with the crankcase through the valve chamber so that much of the oil will be caught by impingement on the valve mechanism and the walls of the chamber and will not be drawn into the carburetor.

I have also so designed the assembly that the single bolt or stud usually employed to hold the valve cover in place may, by slight 40 modification, be employed to hold the ventilating connection in place.

In the drawing:

Figure 1 is a vertical section through an internal combustion engine to which my ventilating system is applied.

Figure 2 is a side elevation of the arrangement of Figure 1.

Figure 3 is a section on line 3—3 of Figure 2. On the drawing, 10 indicates an internal combustion engine having a crankcase 12 provided with the conventional breather 14 for admitting air to the crankcase. The breather is illustrated as equipped with a screen 16 for intercepting dust. To the breather cap is secured a rod 18 which may be used to indicate the level of oil in the crankcase. At 20 I have shown the usual carburetor supplying the engine with fuel and equipped with an air intake 22 upon which is mounted an air cleaner 24. The cleaner comprises a cylindrical casing 26 provided at 28 with an annular series of helical blades for imparting a whirling motion to the entering air. At the other end of the casing the cleaner is provided with a dust discharge slot 30. 32 represents the clean air outlet which is equipped with the air straightener 33. In this type of cleaner it is obvious that the helical blades cause the air to whirl, segregating the dust in the outer layers and eventually effecting its discharge 75 through the slot 30. The clean air then reverses its direction and passes outwardly through the outlet 32. The air straightener takes the whirling motion out of the air as it enters the carburetor.

34 indicates the valve chamber housing parts of the valve mechanism such as the usual valve stems, springs and tappets. These chambers are in communication with the crankcase through passages 36. The valve chambers are provided with covers 38. Conduit 40 establishes communication between one of the valve chambers and the center of the casing 26 of the cleaner. The conduit is preferably S-shaped, as shown, and from the engine wall extends stud 41 passing through the aperture in the valve cover and through the conduit 40. A nut 44 is engaged on the stud for clamping the conduit and cover to the engine block.

With this arrangement it is apparent that the air drawn out of the crankcase is replaced by fresh air through the breather 14. Crankcase vapors find admission to the air cleaner at the center of the vortex where the suction

is high so that circulation of air through the crankcase is promoted. By drawing the crankcase vapors through the valve chamber the particles of oil carried thereby are caused 5 to impinge upon the valve mechanism and the walls of the chamber so that the vapors passing to the carburetor are relatively free of oil. If desired, special means such as baffles may be provided in the conduit 40 leading crank- 10 case vapors to the cleaner for the purpose of more effectively separating the oil particles therefrom. However, I prefer to make use of the valve chamber for this purpose.

I claim:

15 1. An internal combustion engine having a crankcase having an air inlet, a suction operated air intake, an air cleaner for the intake, said cleaner including means for whirling the air and an outlet for clean air leading 20 from the center of the vortex, and a connection from the crankcase to the center of the vortex for withdrawing air from the crankcase and delivering it directly to the clean air outlet without undergoing cleaning action.

25 2. In the combination as defined in claim 1, said engine having a valve chamber in communication with the crankcase and said connection leading from the valve chamber so as 30 to effect separation of oil particles from the vapors in their passage through the chamber.

35 3. An internal combustion engine having a crankcase provided with an air inlet, a suction operated air intake and an air cleaner for the intake provided with means for separating dust from the air and with an axial clean air outlet, and a conduit communicating with the crankcase and connected with the cleaner in alignment with the clean air outlet 40 so that the vapors passing into the cleaner from the crankcase discharge directly into the clean air outlet without undergoing cleaning action.

45 4. An internal combustion engine having a crankcase provided with an air inlet, a valve chamber communicating with the crankcase, a cover for the valve chamber, a suction operated air intake, an air cleaner for the intake provided with means for separating dust 50 from the air and with an axial clean air outlet, and a conduit mounted on the cover and connected to the cleaner in alignment with the clean air outlet so that the vapors passing into the cleaner from the crankcase discharge directly into the clean air outlet without undergoing cleaning action.

55 5. An internal combustion engine having a crankcase provided with an air inlet, a valve chamber communicating with the crankcase, a suction operated air intake, an air cleaner for the intake provided with means for separating dust from the entering air and with an axial clean air outlet, and a conduit communicating with the valve chamber and con-

nected to the cleaner in alignment with the clean air outlet so that the vapors passing into the cleaner from the crankcase discharge directly into the clean air outlet without undergoing cleaning action.

70 In testimony whereof I affix my signature.
CHARLES L. McCUEN.
